US00D551760S

(12) **United States Design Patent** (10) **Patent No.:** **US D551,760 S**
Zahn et al. (45) **Date of Patent:** **** Sep. 25, 2007**

(54) **DISPENSING CONTAINER-SINGLE CHANNEL**

(75) Inventors: **Walter Zahn**, Columbia, SC (US);
Shawn W. Miller, Columbia, SC (US);
David Rocheleau, Lexington, SC (US);
Mohammad R. Sadeghi, Columbia, SC (US);
Bernd Hansen, Laufen (DE)

(73) Assignee: **Holopack International Corp.**,
Columbia, SC (US)

(**) Term: **14 Years**

(21) Appl. No.: **29/243,354**

(22) Filed: **Nov. 23, 2005**

(51) **LOC (8) Cl. 24-02**

(52) **U.S. Cl. D24/115; D24/117**

(58) **Field of Classification Search** D24/193-99,
D24/115, 117, 56-58, 63; D3/178, 393-4;

(57) **CLAIM**

The ornamental design for a dispensing container-single channel, as shown and described.

DESCRIPTION

FIG. 1 is a front perspective view of a dispensing container-single channel of the present invention;

FIG. 2 is a top plan view thereof;

FIG. 3 is a bottom plan view thereof;

FIG. 4 is a right side elevational view thereof;

FIG. 5 is a front elevational view thereof; and,

FIG. 6 is a back elevational view thereof.
